DESIGN FOR A ROOF MOUNTED AIR CONDITIONER FOR VEHICLES OR SIMILAR ARTICLE

Ralph F. Peo, Buffalo, N. Y., assignor to Houde Engineering Corporation, Buffalo, N. Y., a corporation of New York

Application October 31, 1936, Serial No. 65,613

Term of patent 7 years

To all whom it may concern:

Be it known, that I, Ralph F. Peo, a citizen of the United States and residing in the city of Buffalo, in the county of Erie and State of New York, have invented a new, original, and ornamental Design for a Roof Mounted Air Conditioner for Vehicles or Similar Article, of which the following is the specification, reference being had to the accompanying drawing, forming a part thereof.

On the drawing:

Figure 1 is a side elevational view of a roof

mounted air conditioner or similar article showing my new design.

Figure 2 is a top plan view of the air conditioner or similar article shown in Figure 1.

Figure 3 is a front elevational view of the air conditioner or similar article shown in Figure 1.

I claim:

The ornamental design for a roof mounted air conditioner for vehicles, or similar article, substantially as shown.

RALPH F. PEO.
